UNITED STATES PATENT OFFICE.

LEWIS METESSER, OF NEW ORLEANS, LOUISIANA.

FUEL-AGITATING MEANS FOR FURNACES.

1,177,430.

Specification of Letters Patent. Patented Mar. 28, 1916.

Application filed April 10, 1915. Serial No. 20,510.

To all whom it may concern:

Be it known that I, LEWIS METESSER, a citizen of the United States, residing at New Orleans, in the parish of Orleans and State of Louisiana, have invented certain new and useful Improvements in Fuel-Agitating Means for Furnaces, of which the following is a specification.

My invention relates to improvements in fuel agitating means for furnaces, stokers, or the like.

An important object of the invention is to provide an agitator adapted to be arranged in the magazine or retort of a stoker or beneath the grates, while not necessarily restricted to such use, and which is simple in construction, inexpensive to manufacture, durable and will thoroughly agitate the coal for properly liberating the gases before ignition and complete combustion is possible, and also thereby preventing the fuel from coking.

A further object of the invention is to provide means of the above mentioned character, adapted to be automatically operated upon the movement of the feed plunger.

Other objects and advantages of the invention will be apparent during the course of the following description.

While I have shown and described my agitating means in combination with the elements of an under-feed stoker, it is to be understood that such agitating means is not solely restricted to the use in such combination, as the same may be employed successfully in connection with the elements of various furnaces and stokers.

In the accompanying drawings forming a part of this specification and in which like numerals are employed to designate like parts throughout the same, Figure 1 is a side elevation of an under-feed stoker, showing my apparatus applied thereto, Fig. 2 is a plan view of the same, Fig. 3 is a central vertical longitudinal sectional view through the same, parts being shown in elevation, and, Fig. 4 is a transverse sectional view taken on line 4-4 of Fig. 3.

In the drawings, wherein for the purpose of illustration is shown a preferred embodiment of my invention, the numeral 5 designates a magazine, retort or trough of an under-feed stoker, which is arranged between and beneath the grate-sections of a furnace, as is well known in the art. This magazine has its upper side open and is

provided with a horizontal laterally extending flange 7, having recesses or pockets 8.

The numeral 10 designates twyers, arranged upon the flanges 7 and carrying depending lugs 11, entering the pockets 8, as more clearly shown in Fig. 4.

Arranged within the upper portion of the magazine 5 between its ends are vertically swinging agitator elements or bars 12, pivoted between their ends with the side walls of the magazine, by means of bolts 13 or the like. Pivots connected preferably with the rear ends of the agitator elements or bars 12 is a preferably U-shaped connecting link 14 including two arms 14', which are pivotally connected with an agitator block 15, as shown. This agitator block is rigidly mounted upon a reciprocating rod 16 which has its rear end operating in a guide sleeve 17, as shown. Any other suitable means may be employed to pivotally connect the substantially U-shaped link 14 with the rod 16.

Bolted or otherwise rigidly attached to the forward end of the magazine 5 is a fuel feed casing or cylinder 18, having a feed hopper 19, bolted thereto, as shown. The upper portion of the feed casing is provided with an opening 20, normally covered by a plate 21, held in place by bolts 22.

Disposed to reciprocate within the feed cylinder 18 is a feed plunger 23, which is preferably hollow and adapted to force the fuel from the feed cylinder 18 into the magazine 5. Extending longitudinally within the hollow feed plunger 23 is a connecting rod 24, rigidly connected with the rear end thereof and provided at its forward end with a depending extension or crank 25, operating through an elongated slot 26 formed in the lower portion of the feed casing 18. The extension 25 is pivotally connected with the rod 16 by a bolt 27 or the like.

The numeral 28 designates a steam engine cylinder which is bolted or otherwise rigidly secured to the forward end of the feed cylinder 18. Mounted to reciprocate within the cylinder 28 is a piston 29, rigidly connected with a piston rod 30 extending rearwardly into and through the hollow plunger 23 and rigidly secured to the rear end thereof.

The cylinder 28 is provided with a balanced rotary piston valve 31, embodying means for introducing steam or other fluid

pressure into the opposite ends of the cylinder 28, to effect a reciprocation of the piston 29, and elements connected therewith to be moved thereby. The valve 31 is operated by a valve stem or rod 32, mounted to slide in stationary guides 33, bolted or otherwise rigidly secured to the casing 18. Rings or collars 34 are rigidly mounted upon the stem or rod 32 and are adapted to be engaged by a head 35 sliding upon the rod 32 and formed integral with an arm 36, having its lower end rigidly secured to the extension 25 by any suitable means.

The operation of the apparatus is as follows: As the piston 29 reciprocates in the cylinder 28, the plunger 23 moves with it in the feed cylinder 18, whereby the fuel passing downwardly from the hopper 19 is fed into the magazine 5, and forced upwardly therefrom upon the grate or grate-sections of the furnace, as is customary in under-feed stokers. The movement of the piston 29 through the medium of the associated elements, serves to automatically operate the valve 31, controlling the inlet and exhaust of the fluid pressure to and from the opposite ends of the cylinder 28, as in the operation of the ordinary steam engine. The movement of the plunger 23 reciprocates the rod 16, whereby the substantially U-shaped link 14 is made to alternately assume forward and rear inclined positions as illustrated in Fig. 3. This movement of the link causes the agitator elements or bars 12 to alternately assume rearwardly and forwardly inclined positions. I have found that the agitator bars 12 and links 14 by vertically swinging in the presence of the fuel, are very effective in breaking up and agitating the fuel.

It is to be understood that the form of my invention herewith shown and described is to be taken as a preferred example of the same, and that various changes in the shape, size, and arrangement of parts may be resorted to without departing from the spirit

of the invention or the scope of the subjoined claims.

Having thus described the invention, I claim:—

1. The combination with a magazine of an underfeed furnace, of normally approximately horizontal agitator bars arranged therein adjacent the opposite sides thereof, a reciprocatory rod operating within the bottom of the magazine, means pivotally connecting the rod with corresponding ends of the agitator bars, and means to feed material into the magazine and to move the rod.

2. The combination with a magazine having its upper side open, of agitator bars pivotally connected with the upstanding sides of the magazine and arranged within the magazine near its upper open side, a substantially U-shaped link pivotally connected with the bars and depending therefrom, a reciprocatory rod mounted to move in the lower portion of the magazine and having pivotal connection with the link, means to feed fuel into the magazine, and means to reciprocate the rod.

3. The combination with a magazine of an under-feed stoker, of a pair of spaced agitator bars pivotally mounted within the upper portion of the magazine to swing in a substantially vertical plane, a reciprocatory rod arranged in the bottom of the magazine, a link pivotally connecting corresponding ends of the agitator bars with the rod, a feed casing secured to one end of the magazine, a plunger mounted to reciprocate within the feed casing, means connecting the plunger and rod, and means to reciprocate the plunger.

In testimony whereof I affix my signature in presence of two witnesses.

LEWIS METESSER.
